UNITED STATES PATENT OFFICE.

JOHN S. McCLURG, OF NEWARK, OHIO, ASSIGNOR TO THE PHARIS TIRE & RUBBER COMPANY, OF NEWARK, OHIO, A CORPORATION OF OHIO.

DESIGN FOR A RUBBER TIRE.

46,367.

Specification for Design.

Patented Sept. 8, 1914.

Application filed July 13, 1914. Serial No. 850,835. Term of patent 7 years.

To all whom it may concern:

Be it known that I, JOHN S. McCLURG, a citizen of the United States, residing at Newark, Licking county, Ohio, have invented a new, original, and ornamental Design for Rubber Tires, of which the following is a specification, reference being had to the accompanying drawing, forming part thereof, in which—

Figure 1 is a view of the tread face of the

tire, and, Fig. 2 is a transverse section of my newly designed tire taken on line $x-x$ of Fig. 1.

I claim:

The ornamental design for a rubber tire, as shown.

JOHN S. McCLURG.

Witnesses:

CARL PHARIS,

J. R. WALTERS.
